UNITED STATES PATENT OFFICE.

CHARLES H. DAMMAN, OF CHICAGO, ILLINOIS.

SHIRT-HOLDER.

Specification of Letters Patent. Patented July 14, 1914.

1,103,742.

Application filed March 18, 1913. Serial No. 755,232.

To all whom it may concern:

Be it known that I, CHARLES H. DAMMAN, a citizen of the United States, residing at Chicago, in the county of Cook and State of Illinois, have invented certain new and useful Improvements in Shirt-Holders; and I do hereby declare the following to be a full, clear, and exact description of the invention, such as will enable others skilled in the art 5 to which it appertains to make and use the same.

This invention comprehends improvements in shirt holders and relates more particularly to those which are especially adapted for holding laundry shirts.

The primary object of the invention resides in the provision of a holder of this type, which shall be of extremely simple construction, cheap to manufacture, and 20 which will maintain a shirt in a neat, convenient manner without the use of pins, bands, etc.

Another and more specific object of the invention resides in the provision of a shirt holder which may be stamped from a sheet 25 of cardboard, and which includes a slotted body portion and rear sections hinged thereto, one of said rear sections being formed with locking tongues for insertion with slits 30 formed within the other of said rear sections.

The invention also aims to generally improve holders of this nature to render them more useful, practical, and commercially desirable.

With these and other objects in view, as will become more apparent as the description proceeds, the invention consists in certain novel features of construction, combination, and arrangement of parts, as will be 40 hereinafter described and claimed.

For a complete understanding of my invention, reference is to be had to the following description and accompanying drawings, 45 in which,

Figure 1 is a plan view of my holder in its open position, Fig. 2 is a front view of the holder, showing a shirt positioned therein, and, Fig. 3 is a fragmentary sectional view taken on the plane of line 3-3 of

Fig. 2.

My improved shirt holder is preferably formed from a sheet of cardboard or similar material and includes a body section, generally designated 5, and rear sections 6 and

7. The body section is essentially rectangular in shape, has its upper edge cut away, as indicated at 8, to form an opening for the collar band, and is formed with transverse slots 9 and 9', which divide it into a 60 relatively narrow upper section 10, an intermediate section 11, and a lower section 12. The rear sections 6 and 7 are formed by bending the sheet of material along the dotted lines 13. The section 6 carries upon its 65 free edge the locking tongues 14 which have their opposed edges notched, as indicated at 15. These locking tongues are adapted when the holder is in its operative position, to overlap the section 7 and project partially 70 through the slits 16 formed therein. The edges of the notches 15 engage the material surrounding the inner ends of the slits 16 so as to hold the tongues within the slits.

In use, a shirt 17, which is folded as 75 clearly shown in Fig. 2, is secured to the body portion by being extended through the slots 9 and 9' so that the end sections 10 and 12 will be disposed in front of the shirt and the intermediate section 11 will be 80 disposed behind the shirt. The rear sections are then folded so as to engage the back of the shirt and the rear surface of the central section, and are maintained in this position by the locking tongues 14.

It will be seen from the foregoing description taken in connection with the accompanying drawings, that I have provided a shirt holder of extremely simple construction, in which a shirt may be easily and conveniently secured, and held without the use of pins or other fasteners. It is to be noted that the rear sections 6 and 7 reinforce the body section and prevent the holder from 85 being easily folded.

It is to be understood that while I have shown and described the preferred embodiment of my invention, I do not wish to be limited to this exact construction, combination, and arrangement of parts, but may 90 make such changes as will fall within the spirit and scope of the invention.

Having thus described my invention, what I claim is:-

The herein described shirt holder comprising a rectangular body portion formed of paper and provided with a pair of transverse slots adjacent the ends thereof, whereby said body portion is divided into three sections, one of said sections being cut away 110

on a curved line adjacent its outer end to receive the neck band of a shirt, a pair of rear sections hinged to the side edges of the body portion, and locking tongues on one of said sections having angular notches therein and slits in the other section for securing said rear sections to each other in engagement with the body, the end sections of the body being adapted to engage the

front of a shirt to hold said shirt against 10 the rear section.

In testimony whereof I affix my signature in presence of two witnesses.

CHARLES H. DAMMAN.
